ELECTRIC LIGHT SOCKET

Filed June 21, 1929

Fig. 1.

UNITED STATES PATENT OFFICE

JOSEPH L. WHATLEY, OF HOMESTEAD, PENNSYLVANIA

ELECTRIC-LIGHT SOCKET

Application filed June 21, 1929. Serial No. 372,666.

My present invention has reference to a novel construction of sockets for electric lamp bulbs, the primary object being the provision of a socket which has an outer one-piece shell of porcelain, glass or of an insulating composition which may be highly ornamented, colored, or painted to correspond with the papering or trimming of the room, which will support thereon a shade for the lamp bulb and which perfectly insulates the socket proper from circuit and mechanical deficiencies or difficulties.

A further object is the provision of a key socket in which porcelain sections to which the key switch, the wires, the central lamp bulb contact and the metal screw base are enclosed and supported in an outer shell of insulating material in a simple, but novel and thoroughly effective manner.

A still further object is the provision of a device for this purpose in which the internally threaded shank of an operating key is screwed into the shaft for the contact switch, and wherein the said switch is held from turning except in one direction, such turning of the switch both making and breaking the circuit to the lamp bulb.

To the attainment of the foregoing and other objects which will present themselves, the improvement also resides in certain other novel features of construction, combination and operative association of parts, one satisfactory embodiment of which is disclosed by the drawings.

In the drawings:

Figure 1 is a substantially central vertical sectional view through the improvement.

Figure 2 is a sectional view approximately on the line 2—2 of Figure 1.

Figure 3 is a sectional view approximately on the line 3—3 of Figure 2.

Figure 4 is a perspective view of the nut member employed.

Figure 5 is a similar view of a porcelain supporting yoke.

The porcelain portion of my improved socket is formed of two sections in the usual manner. These sections 1—1, are connected by bolts 2 and 3, respectively. The bolt 3

50 has attached to what I will term its upper

end the terminal 4 for one of the covered conductor wires 5. This bolt 3 is, therefore, in the nature of an electric conductor. The terminal for the second conductor wire is let in a pocket in the upper porcelain section 1 and is indicated by the numeral 6. The terminal has screwed thereon a bolt 7 whose headed end engages the offset end of a spring contact plate 8. The contact plate passes through a suitable opening or depression in the confronting faces of the porcelain sections 1 and the said spring contact is disposed opposite the inwardly directed spring arm 9 on the upper end of a metal plate 10, the lower end of the plate being directed inwardly and received in a depression in the lower porcelain member 1 and merging into a downwardly projecting portion that terminates in a cup-shaped end that forms a central contact 11. The outer face of the lower porcelain member 1 has riveted or otherwise secured thereon a fibre washer 12, the arm 9 providing with the spring arm 8 contact makers.

The screw base of the socket is indicated by the numeral 13 and has its top portion secured to the porcelain by the bolts 2 and 3 and the central contact 11 passes through an opening in the said top of the screw base 13. The base 13 has secured upon its sides, adjacent to its upper and non-threaded end the straight ends of equidistantly spaced curved springs 14 and these springs contact with the inner face of the outer shell 15 of the improvement. The shell 15 may be constructed of glass, porcelain or some suitable composition that is of non-electric conductivity. The mouth of the base 13 is received in the mouth of the shell, and the shell adjacent to its lower end is provided with peripheral ribs 16 whereby a shade may be attached thereto. The shell in the showing of the drawings is round in cross section but may, of course, be of any desired shape or contour and the top of the shell is preferably inclined from its center to the sides thereof, the said top being centrally formed with an outwardly directed flange 17 that surrounds a round opening in the said top. Received through this opening there is the threaded and hollow

cylindrical shank 18 of a nut member 19. The nut member is also interiorly threaded whereby the socket may be attached to a suitable pipe support, and through the hollow nut the circuit wires 5 and 20 pass. A washer 21 is arranged between the nut and the flange 17, and the hollow cylindrical extension 18 of the said nut is screwed through a threaded opening in the top of the yoke member 22, best illustrated by figure 5 of the drawings. The yoke member is received in vertical depressions in the sides of the porcelain member 1—1 and is secured to the lower porcelain member by rivets or bolts 23. In this manner it will be noted that the mechanical portion of the improvement is effectively supported in the shell 15, and that the arched springs 14 on the base 13 serve as cushioning as well as spacing elements between the base 20 and shell.

The switch which forces the spring contact 8 against the metal end 9 of the central contact 11 is in the nature of a substantially rectangular block and is indicated by the numeral 24. The block has its edges, adjacent to its opposite corners notched, as at 25. A shaft 26 passes centrally through the switch 24 and is fixed thereto. The shaft is journaled through openings in upstanding lugs 30 on the ends of a plate 27 that is suitably supported in the cut-away or hollow portions of the porcelain members 1 and the shaft is formed with stop elements 28 that contact with the ears 29 for preventing the longitudinal movement of the said shaft through its bearings. One end of the shaft is threaded, and the porcelain members 1, as well as the shell 15, have round alining openings. The openings in the porcelain member 1 receive the threaded end of the shaft 26 therein. The numeral 30 indicates a key member which, of course, is of insulating material and which is provided with a shank or stem that has an internal threaded bore, the depth of which corresponds approximately to the length of the threads of the shaft 26. The key 30 is screwed on the shaft. The switch 24 can turn only in one direction, that is, to swing the contact spring 8 against the contact 9 to complete the circuit from the conductor wires to the contacts 11 and to the base 13 and thus illuminate a lamp bulb which is screwed in the base, a further turning of the switch in the same direction bringing the switch to the position illustrated by Figure 3 of the drawings and causing the spring contact maker 8 to swing away from the contact maker 9.

The simplicity of my construction and the advantages thereof will, it is thought, be understood and appreciated when the foregoing description has been read in connection with the accompanying drawings, so that further detailed description will not be required, it being noted that I have provided both a safe and novel construction of electric light sock-

ets and one which may be highly ornamented to add to the attractiveness of the room in which it is located. Obviously I do not wish to be restricted to the precise details herein set forth and, therefore, hold myself entitled to make such changes therefrom as fairly fall within the scope of what I claim.

As disclosed by Figure 1 of the drawings the porcelain body of the improvement has its neck portion provided with an annular recess in which is received a fibre washer 35. This washer is contacted by the yoke member 22 so as to prevent the said yoke from inflicting injury on the porcelain body when the part 18 of the nut member is screwed thereon. The head 19 of the nut member is provided with an opening for the reception of a screw or bolt that has a kerfed end 36. The bolt is designed to engage with the electric conductors and hold the same in the said bolt. The spring arms 8 and 9 may, of course, be shortened or lengthened to aid in properly positioning the key in the improvement.

Having described the invention, I claim:

1. An electric light socket including porcelain sections and a screw base, a fibre washer between the lower section and the screw base, means comprising bolts securing the screw base to the porcelain sections and connecting said sections, wire terminals in the upper porcelain section for electric conductors, one of which being secured to one of the bolts, a spring contact to which the second electric conductor is connected, a central contact entering the screw base having a portion received in the lower porcelain section and riveted thereto and having an upstanding end terminating in an inwardly directed arm that is disposed opposite the spring contact, a switch member normally resting on the spring contact and turnable in one direction, a shaft for the switch member, a shell of non-electric conductivity for the socket, means secured on the shell for supporting the porcelain sections therein, spring spacer means carried by the screw base and contacting with the inner wall of the shell and a key member having a shank portion received through the socket and screwed on the shaft.

2. An electric light socket including porcelain sections having a screw base and said porcelain sections having a fibre washer between the lower section and the base, means comprising bolts securing the screw base to the porcelain sections and connecting said sections, wire terminals in the upper porcelain section for electric conductors, one of which conductors being secured to one of the bolts, a spring contact maker secured to the second terminal and to which terminal the second electric conductor is connected, a contact in the base having an extension projecting into the lower porcelain section and ter-

minating in an arm which is disposed opposite the spring contact maker, a switch block normally resting on the spring contact maker and rotatable to force the said contact maker 5 into engagement with the arm, a shaft for the switch block, a handle of insulating material removably secured to one end of the shaft, a shell of non-electric conductivity for the socket, a nut member having a hollow shank 10 screwed through the top of the shell and through which the conductor wires are directed, a yoke in the shell screwed on the shank and having its arms secured to the lower porcelain section, and arched spacer 15 springs secured to the screw base and contacting with the shell.

In testimony whereof I affix my signature.
JOSEPH L. WHATLEY.
